UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

VACUUM PUMP.

Application filed May 3, 1924. Serial No. 710,730.

In the patents to Leitch, No. 1,367,554, February 8, 1921, and Hall, No. 1,374,650, April 12, 1921, there is described a vacuum pump which has gone into successful commercial use. The object of the present invention is to so modify the construction of this Leitch-Hall pump, or of other pumps of a similar type, so as to substantially reduce the cost of manufacture.

In the manufacture of the Leitch-Hall pump, the provision of the described air channels in the housing requires the use of blind cores in the casting operation and involves also the cutting of ports in the circular wall, or bore, of the housing. In my improved construction, the bore of the housing is maintained imperforate and no blind cores are required in the casting operation.

In the Leitch-Hall pump, the bore of the housing is of such shape that all diameters (or chords) measured through the center of the shaft are equal. This involves giving an elliptical shape to the bore of the housing. This operation requires highly skilled labor and care and if not performed accurately, produces rough running of the rotor. In my improvement, the bore of the housing is made circular, with other modifications of construction to render a housing so shaped operative. Not only is such a housing relatively easy and inexpensive to produce, but smoothness of operation is thereby secured with more certainty than in the older construction.

The invention will be understood by reference to the drawings, which illustrate a preferred embodiment of the invention.

Fig. 1 is a cross-section through the housing, rotor and oil separator.

Fig. 2 is a section, on a somewhat reduced scale, on the line 2—2 of Fig. 1; certain elements, such as the shaft driving mechanism, lubricating oil channels, etc., being omitted.

Fig. 3 is a section through the line 3—3 of Fig. 1.

Fig. 4 is a section through the line 4—4 of Fig. 1.

Fig. 5 is a section through the line 5—5 of Fig. 1.

The rotor *a* is mounted on a shaft *b* carried by bearings in the heads *c* and *d*. Between the heads is a housing *h*. The bore of the housing is circular (a true cylinder).

The shaft *b* is located on a diameter of the bore of the housing, but not at the center

of the bore. In the drawings, it is located directly above such center. Therefore, a horizontal chord through the center of the shaft is the shortest chord through the center of the shaft while a vertical chord through the center of the shaft (which coincides with the diameter of the housing) is the longest chord through the center of the shaft, other chords being of progressively variable mediate lengths.

The rotor has four slots in which wings or vanes *e* slide toward and from the shaft. There are two pairs of spacers *f*, one pair for each pair of oppositely disposed vanes. Each spacer is provided with a seat *x* for the inner ends of opposite vanes, which are maintained a minimum distance apart by their corresponding spacers; but each vane is capable of moving out, under the influence of centrifugal force, so as to maintain the semi-circular rods *g* (oscillatable in grooves in the outer edges of the vanes) in continuous contact with the circular bore of the housing. Preferably, although not necessarily, opposite vanes seat in their sockets at the instant they occupy a position coincident with the shortest chord through the center of the shaft. In other positions, one at least of the vanes moves radially outward so that its inner edge recedes from its seat, leaving a clearance, as shown at *y*, Figs. 1 and 2.

The mode of operation, in general, is the same as that of the Leitch-Hall pump.

With the pump running at high speed, say 500 to 650 R. P. M., no spacers are necessary, as the centrifugal force will be great enough to keep the wing tips in contact with the bore of the housing at all times. Their provision, however, is distinctly advisable.

It is obviously much easier to make the bore of the housing circular than to make it elliptical, especially where the ellipse must be formed so accurately that all chords measured through the center of the shaft are equal. Unless that is done quite accurately, the pump will chatter more or less. In the present construction, not only is accuracy of contour much more easily secured, but any departure from accuracy will be compensated for by the capacity of the vanes to automatically adjust themselves thereto, so that smooth running is insured.

Within each head *c*, *d*, at one side thereof (the left hand side, Figs. 1 and 3) is formed

a long arcuate air inlet chamber i opening toward the housing and rotor. The outer wall of each chamber i is curved on an arc whose center is the center of the cylindrical housing. So, also, is the inner wall, throughout the greater part of its length. The outer wall of each chamber i is a substantial distance beyond the bore of the housing. The inner wall of each chamber i is a short distance within the bore of the housing, leaving a narrow elongated arcuate orifice j for passage of air from chamber i to the space between the rotor and housing bore. In that end (the upper end) of the chamber nearest the line of tangential contact between rotor and housing bore, the inner wall of the chamber coincides with the outer wall of the rotor, whereby tendency to leakage of air is avoided. A cross-channel m is formed through the housing to connect opposite air chambers i , i . The housing is threaded at n to receive an air suction pipe (not shown).

Within each head c , d , at the upper right hand corner is formed an air outlet chamber or recess o opening inward. The inner edge of each recess o overlaps the bore of the housing, affording a slotted opening p for passage of air from the space between the housing bore and rotor to such recess. The inner edge of each recess o throughout the greater part of its length is coincident with the outer wall of the rotor, so that the slotted opening p is tapered throughout the greater part of its length. In the housing are formed channels r , r , opening laterally into the respective recesses o , o , and communicating, through ports s , s (see Fig. 5), with the oil separator t (the specific construction of which need not be described, as it forms no part of this invention). The oil separator is threaded in its upper wall at u to receive an air exhaust pipe (not shown). The construction just described eliminates some of the worst of the cores required to make the form of Leitch-Hall construction specifically disclosed in the patents hereinbefore mentioned. Further, by providing for discharge of air through the side, instead of through the center of the housing, more space is allowed for the air to flow through the separating chamber into the outlet u . This construction has been found by test to considerably relieve the back pressure on the discharge side of the pump, thus reducing the power consumption.

In Fig. 2, there is shown applied to the head c a rotary pulsator valve v geared to the shaft b . This valve need not be described, as it forms no part of the present invention.

In casting the described construction, the formation of the channels i , m , o and r requires no blind cores and presents no other

manufacturing difficulties, while the bore of the housing may be left entirely imperforate.

Having now fully described my invention, what I claim and desire to protect by Letters Patent is:

1. In a vacuum pump of the sliding vane type, the combination with a driving shaft, a rotor mounted thereon and oppositely disposed vanes extending through slots in the rotor and slidably radially therein, of a housing enclosing the rotor and vanes and having a true circular bore whose center is offset relatively to the center of the shaft, and slidable spacers between oppositely disposed vanes limiting the approach of such vanes toward each other but permitting their relative recession.

2. In a vacuum pump of the sliding vane type, the combination with a driving shaft, a rotor mounted thereon and oppositely disposed vanes extending through slots in the rotor and slidably radially therein, of a housing enclosing the rotor and vanes and having a true circular bore, the center of the shaft being positioned on a diameter of the housing bore at one side of the center thereof, and spacers slidable independently of the vanes and in the ends of which oppositely disposed vanes are adapted to seat, each spacer just filling the space between such vanes when the same occupy a position on the shortest chord subtended by such vanes in their rotation.

3. In a vacuum pump of the sliding vane type, the combination with a driving shaft, a rotor mounted thereon, a housing enclosing the rotor, and vanes extending through slots in the rotor and slidably radially therein and engaging the bore of the housing, of heads closing the ends of the housing, each head provided with an air chamber the edge of which overlaps the bore of the housing and affords a narrow opening for air communication between said chamber and the space between the bore of the housing and the rotor, the bore of the housing being imperforate.

4. In a vacuum pump of the sliding vane type, the combination with a driving shaft, a rotor mounted thereon, a housing enclosing the rotor and having an imperforate bore, and vanes extending through slots in the rotor and slidably radially therein and engaging the bore of the housing, of heads closing the ends of the housing, each head provided with an air chamber the edge of which overlaps the bore of the housing and affords a narrow opening for air communication between said chamber and the space between the bore of the housing and the rotor, the housing having a channel parallel to the axis of the shaft extending entirely through the housing and connecting the air chambers in opposite heads.

5. In a vacuum pump of the sliding vane type, the combination with a driving shaft,

- a rotor mounted thereon, a housing enclosing the rotor and having an imperforate bore, and vanes extending through slots in the rotor and slidably radially therein and engaging the bore of the housing, of heads closing the ends of the housing, each head provided with an air chamber opening toward the housing, the wall of the chamber nearest the center of the housing being, throughout the greater part of its length, curved on an arc substantially concentric with, and overlapping, the bore of the housing, and being curved along another part of its length eccentrically with the bore of the housing and in substantial coincidence with the outer cylindrical wall of the rotor, forming thereby an elongated narrow arcuate air inlet port of uniform width along the greater part of its length and tapered in width along another part of its length. 40
- 5 6. In a vacuum pump of the sliding vane type, the combination with a driving shaft, a rotor mounted thereon, a housing enclosing the rotor and whose bore is imperforate and is disposed eccentrically to, and tangentially engaged by, the rotor, and vanes extending through slots in the rotor and slidably radially therein and engaging the bore of the housing, of heads closing the ends of the housing, each head provided with an air chamber the edge of which overlaps the bore of the housing and substantially coincides along part of its length with the outer cylindrical wall of the rotor. 45
- 10 7. In a vacuum pump of the sliding vane type, the combination with a driving shaft, a rotor mounted thereon, a housing enclosing the rotor and having an imperforate bore, and vanes extending through slots in the rotor and slidably radially therein and engaging the bore of the housing, of heads closing the ends of the housing, each head provided with an air chamber opening toward the housing, the wall of the chamber nearest the center of the housing being, throughout the greater part of its length, curved on an arc substantially concentric with, and overlapping, the bore of the housing, and being curved along another part of its length eccentrically with the bore of the housing and in substantial coincidence with the outer cylindrical wall of the rotor, forming thereby an elongated narrow arcuate air inlet port of uniform width along the greater part of its length and tapered in width along another part of its length. 50
- 15 8. In a vacuum pump of the sliding vane type, the combination with a driving shaft, a rotor mounted thereon, a housing enclosing the rotor, and vanes extending through slots in the rotor and slidably radially therein and engaging the bore of the housing, of heads closing the ends of the housing, each head provided with an air chamber the edge of which overlaps the bore of the housing and affords a narrow opening for air communication between said chamber and the space between the bore of the housing and the rotor, said housing having, outside the wall forming its bore, a channel communicating laterally with said chamber, and an oil separating chamber outside said channel and communicating therewith. 55
- 20 9. In testimony of which invention, I have hereunto set my hand at New York, on this 15th day of April, 1924. 60
- 25 10. CYRUS HOWARD HAPGOOD. 65
